FIG. 3

FIG. 4

Des. 200,685

PAGE 4

FIG. 5

FIG. 6

FIG. 7

FIG. 1 is a perspective view of a hair dryer embodying our new design;

FIG. 2 is a top plan view;

FIG. 3 is a front elevational view;

FIG. 4 is a right side elevational view;

FIG. 5 is a rear elevational view;

FIG. 6 is a left side elevational view; and

FIG. 7 is a bottom plan view.

The essential features of the design reside in the full line showing.

We claim:

The ornamental design for a hair dryer or similar article, substantially as shown and described.
